Application May 11, 1953, Serial No. 24,950

Term of patent 14 years

(Cl. D58—12)

To all whom it may concern:

Be it known that I, Christy M. Del Mas, a citizen of the United States of America, residing in the city, county, and State of New York, have invented a new, original, and ornamental Design for a Box, of which the following is a specification, reference being had to the accompanying drawing, forming part thereof.

The figure is a perspective view of a box embodying my new design.

The characteristic features of my new design reside in the ornamentation shown on the upper surface of the box. The sides of the box not shown are plain.

I claim:

The ornamental design for a box, as shown and described.

CHRISTY M. DEL MAS.
